UNITED STATES PATENT OFFICE.

GREGOR MELICK, OF NEW YORK, N. Y.

DESIGN FOR A MUTUAL ADVERTISING BOND.

56,527.

Specification for Design.

Patented Nov. 2, 1920.

Application filed July 9, 1920. Serial No. 395,166. Term of patent 14 years.

To all whom it may concern:

Be it known that I, GREGOR MELICK, a citizen of Armenia, and resident of the city of New York, in the borough of Manhattan, and county and State of New York, have invented a new, original, and ornamental Design for a Mutual Advertising Bond, of which the following is a specification.

Reference being had to the accompanying drawing, forming part thereof in which; the figure is a plan view of a mutual advertising bond.

I claim:

An ornamental design for a mutual advertising bond, as shown.

GREGOR MELICK.
